UNITED STATES PATENT OFFICE.

GEORGE HENRY WHEARY, OF RACINE, WISCONSIN.

TRUNK.

1,166,418.

Specification of Letters Patent. Patented Dec. 28, 1915.

Application filed January 10, 1914. Serial No. 811,319.

To all whom it may concern:

Be it known that I, GEORGE H. WHEARY, a citizen of the United States, and resident of Racine, in the county of Racine and State of Wisconsin, have invented new and useful Improvements in Trunks, of which the following is a description, reference being had to the accompanying drawings, which are a part of this specification.

10 This invention relates to improvements in trunks.

In trunks of the wardrobe type the body of the trunk is divided vertically medially into two hinged together sections and one section is usually provided with drawers and other compartments and the other or wardrobe section is usually provided with hanger tracks having garment hangers mounted thereon. A shoe box or container is also usually positioned in the lower portion of the wardrobe section. In trunks of this type as ordinarily constructed, the contents of the wardrobe section are exposed to view when the trunk sections are in open position and consequently are not protected from dust and dirt and do not present an ornate appearance. Furthermore, it is necessary to close and lock the trunk sections in order to protect the contents thereof against theft or surreptitious use.

It is one of the objects of the present invention to overcome the objectionable features mentioned and provide a trunk in which the wardrobe section of the trunk may be closed and protected when the trunk sections are in open position.

A further object of the present invention is to provide a trunk having an inside door which covers and protects the open side of the wardrobe section of the trunk.

A further object of the invention is to provide an inside door for a trunk section which is combined with and forms part of the shoe box and other containers of the trunk.

A further object of the invention is to provide an inside trunk door in which part of the door may be swung to open position to gain access to a part of the wardrobe section without opening the other part of the door.

A further object of the invention is to provide a trunk of the type described in which the wardrobe section of the trunk is also provided with an inside top which co-acts with the front cover in closing the wardrobe section. 55

A further object of the invention is to provide a trunk of the type mentioned which is of simple and strong construction and is well adapted for the purpose described.

With the above and other objects in view, the invention consists of the improved trunk and its parts and combinations as set forth in the claims, and all equivalents thereof. 65

In the accompanying drawings in which the same reference characters indicate the same parts in all of the views: Figure 1 is a front view of the wardrobe section of the improved trunk, parts being broken away and a portion of the other drawer section being indicated by dotted lines; Fig. 2 is a vertical section thereof taken on line 2-2 of Fig. 1, the upper cover of the wardrobe section being indicated in open position by dotted lines; Fig. 3 is a vertical sectional view of the upper portion of the wardrobe section shown provided with a modified form of door; Fig. 4 is a front view of the wardrobe section provided with another modified form of door, the drawer section of the trunk being indicated by dotted lines; Fig. 5 is a vertical sectional view of the wardrobe section taken on line 5-5 of Fig. 4; Fig. 6 is a front view of the upper portion of the wardrobe section of the trunk provided with another modified form of cover; Fig. 7 is a transverse sectional view thereof taken on line 7-7 of Fig. 6; and Fig. 8 is a detail view of the form shown in Figs. 6 and 7. 80 90

Referring to the drawings the numeral 10 indicates a wardrobe trunk, 11 the drawer section and 12 the wardrobe section which has mounted in the upper portion thereof rails 13 upon which garment hangers 14 are slidably suspended. The forward ends of the rails have extensions 15 hinged thereto which are adapted to swing horizontally outwardly to permit the garment hangers to be moved out of the trunk while suspended on the rails. In order to easily gain access to the hangers of the wardrobe

section the upper end of said section is open and is provided with a top cover 15 hinged to the rear wall of the wardrobe section. The inner side of the top cover is 5 provided with a pad 16 which is adapted to bear on the garment hangers and the garments folded thereover and hold the same in position against accidental displacement during transportation of the trunk. 10 This pad in some cases may be a loose pad interposed between the cover and the hangers.

The front open side of the wardrobe section is closed by a door 17 which forms the outer 15 wall of a shoe box 18 and a container 19 positioned in the front lower portion of the wardrobe section. The said box and container are provided with covers 20 and 21 to permit access thereto when the door is in 20 open position. The door 17 is in two parts in the forms shown in Figs. 1, 2 and 3 and in the Figs. 1 and 2 form the upper portion 17' is hinged to the lower part on a line along the upper edge of the upper container 25 19 and is adapted to swing outwardly and downwardly to open position. The upper door portion 17' is secured in closed position by a lock 22 mounted on the said portion and 30 engaging the top cover. The door 17 proper is removably secured to the lower portion of the wardrobe section 12 by means of depending lugs 23 connected to the lower portion of said door and which enter recesses 24 provided in the wall of the said section. Spring 35 bolts 25 mounted on the upper wall of the container 21 engage locking plates 26 secured to the side walls of the wardrobe section. In order to remove the door it is only necessary to open the upper portion of the 40 cover and release the spring bolts and the door may then be bodily removed from the section.

In the modified form shown in Fig. 3 the upper portion 26 of the door 17 is hinged to 45 the front edge of the top cover 15 and swings downwardly to closed position and is locked to the upper portion of the door 17 by a lock 27.

The forms of door shown in Figs. 4, 5, 50 6, 7 and 8 are in one piece as indicated by the numeral 28 and in these forms the spring bolts 25 are omitted and the upper edge of the door is overlapped by a flange 29 which is carried by the front edge of the inside top 55 cover 30 provided in this form of trunk. The door 28 also carries a lock 31 which locks the door to the inside top cover. The lower portion of the door is secured to the wardrobe section in the Figs. 4 and 5 form in 60 the same manner as before described with relation to Figs. 1, 2 and 3. The inside top cover is provided with the pad 16 before described.

In the Figs. 6, 7 and 8 form the lower securing means are omitted and the door 28 is 65 hinged to the front edge of one of the side walls of the wardrobe section by separable hinges 32 which permit the door to be removed from the said section when the door is swung to open position.

In the forms shown in Figs. 4 to 8 inclusive a top cover 33 is provided which is of sufficient size to cover the upper ends of both sections when said sections are in closed position.

From the foregoing description it will be seen that the trunk is well adapted for the purpose described and that the wardrobe section may be closed and protected while the trunk is in open position.

What I claim as my invention is:

1. A trunk, comprising a body portion divided vertically into two hinged together parts to form a wardrobe section and another section, the wardrobe section having 85 an open front, and a door covering the wardrobe section front, said door carrying a plurality of containers, the upper one of which is smaller than the lower one.

2. A trunk, comprising a body portion 90 divided vertically into two hinged together parts to form a wardrobe section and another section, the wardrobe section having an open front, and a two-part door covering the wardrobe section front, the upper part 95 of the two-part door adapted to be swung to open position independently of the lower part.

3. A trunk, comprising a body portion divided vertically into two hinged together 100 parts to form a wardrobe section and another section, the wardrobe section having a top cover and an open front, a door covering only the open front of said section to permit garments to be removed upwardly out of 105 said section when the front door is closed and the top cover is in open position, and means for securing the door to the said section.

4. A trunk comprising a body portion divided vertically into two hinged together parts to form a wardrobe section and another section, the wardrobe section having a removable top and an open front and a recessed bottom portion, a door covering the 115 open front and having depending lugs which enter the wardrobe section recesses, a shoe box formed in part by said door, and means for locking the upper portion of said door to the top cover.

5. A trunk, comprising a body portion divided vertically into two hinged together parts to form a wardrobe section and another section, the wardrobe section having a removable top and an open front and a 125 recessed bottom portion, a two-part door

covering the open front and having depending lugs which enter the wardrobe section recesses, means for locking the upper portion of the lower part of the two-part door to the wardrobe section, and means for locking the upper part of the two-part door to the said wardrobe section.

In testimony whereof, I affix my signature, in presence of two witnesses.

GEORGE HENRY WHEARY.
